UNITED STATES PATENT OFFICE.

IRVING E. ASKE, OF DULUTH, MINNESOTA.

ELECTRIC LIQUID AND GAS HEATER.

Application filed December 21, 1920. Serial No. 432,345.

To all whom it may concern:

Be it known that I, IRVING E. ASKE, a citizen of the United States, residing at Duluth, in the county of St. Louis and State 5 of Minnesota, have invented certain new and useful Improvements in Electric Liquid and Gas Heaters, of which I do declare the following to be a specification.

My invention relates to liquid and gas 10 heaters or fuel vaporizers for hydrocarbon fuels, and has for its object the provision of an improved atomizing and preheating device for vaporizing such fuel during its passage from a carburetor to an explosive 15 engine. Heretofore there has often been considerable difficulty in starting automobiles in which the engine cylinders and the hydrocarbon fuel have become chilled during inactivity in cold weather, said fuel 20 then failing to vaporize and mix with air in such manner as to promptly produce an effective charge. I am aware of several prior attempts to produce an efficient, satisfactory and economical vaporizer for such 25 purposes, and of various patents therefore, which structures are designed to employ electric heating elements comprising a heating screen, but which call for conductors of high resistance in such screens, which high 30 resistance conductors result in many objectionable conditions both in manufacture and use. One object of my invention is to provide an improved vaporizer for the purposes aforesaid.

My invention consists of the constructions, 35 combinations and arrangements of parts hereinafter described and claimed.

In the drawings, Fig. 1, is a side elevation of a carburetor and of a portion of the 40 engine intake lead pipe, and of my invention positioned therein. Fig. 2, is an interior front elevation of a gasket plate or ring of insulating material. Fig. 3, is a central vertical longitudinal section through 45 said Fig. 2. Fig. 4, is a front elevation of an electric heating element. Fig. 5, is a side elevation of said heating element. Fig. 6, is an interior front elevation of said gasket plate or ring, with said heating element 50 positioned therein. Fig. 7, is a front elevation of a frame upon which said heating element is wound or mounted. Fig. 8, is an end view of said frame. Fig. 9, is a side elevation, partly in central vertical longitudinal section of both of the hereinafter

described gasket plates or rings in operative position with respect to each other and with respect to said heating element in operative position between them. Fig. 10, 55 is a front elevation of said electric heating element, showing cement filling in the space around those portions of the hereinafter described wires and screens extending from the periphery of the central aperture of said frame to the periphery of said frame. 60

In the drawings, 1, is a gasket plate or ring preferably of insulating material, having an aperture 1^a formed therein for the passage of fuel therethrough; said aperture is preferably countersunk as at 1^b to 70 form a frame for the hereinafter described heating element. There are two of such gasket rings, 1 and 2 respectively, as shown in Fig. 9, but since they are substantially alike only one will be particularly described. 75

In said drawings, 3 is a frame of non-combustible material, preferably metal, upon which is wound in any suitable manner, an electric heating element comprising two 80 fine wire screens 4 and 5 spaced from each other and electrically connected in parallel in any suitable manner or by any suitable means with a source of electricity, not shown, preferably a battery. The wires of 85 one screen are wound at approximate right angles to the wires of the other screen so as to preferably produce a heating element of approximate checkerboard design, with a view to very finely dividing the fuel as 90 it passes through the element and bringing all of it into contact with, or very near to the heated wires. It will be observed especially that each screen has a double wall, 95 which walls are spaced from each other and from the walls of the other screen; thus there are three heated spaces or chambers between the front wall of the outer screen and the rear wall of the outer screen, in which spaces the currents of fuel and air 100 may mingle with very material benefit to the vaporizing and mixing operation. The terminals of the two screens are connected in any suitable manner in parallel with such source of electricity, being preferably 105 brought together in passages 1^c and 1^d, respectively, in said gasket rings, and there connected by soldering to binding posts 7 and 8 common to both of said screens. Said screens are preferably wound upon 110

said frame 3, which is preferably thicker at its ends than at its sides, and is adapted to be laid in the countersunk recess of each of said gasket rings, so as to lie half in one of said rings and half in the other, and so that said screens will extend across the fuel passage from said carburetor to said intake manifold. But it is not material whether said frame lie half in one ring and half in the other, or wholly in one ring. The gasket, comprising said gasket rings with the included heating element, is preferably inserted in the pipe line 9 between the carburetor and the engine cylinder (not shown).

In the preferred form of my invention, I fill the spaces around those portions of the screens and screen-wires between the periphery of the aperture in said frame 3, and the periphery of the frame 3 with any suitable cement, as vitreous enamel 10, as shown in Fig. 10, whereby fluid is prevented from temporarily collecting in such spaces. This feature is an important one, since without such filling moisture sometimes collects, temporarily, in such spaces and is later blown out into the cylinder, the mixture being, therefore, too lean at some periods and too rich at others.

In operation, the chilled air and gasoline or other liquid, or part liquid and part gas, fuel passes through the heated screens and chambers and the liquid portion is atomized and vaporized and thoroughly mixed with the air. The wire used for the screens may be of comparatively low resistance, and is preferably so fine as to sharply cut the liquid drawn against it, instead of constituting a blunt obstacle. The preferred method of winding around the outside of said frame, permits the economical use of winding machines and obviates the need of manual winding, and the arrangement of the screens provides heated interscreen chambers, and the device is prompt in producing the desired result.

What I claim is:—

1. The combination of a frame having an aperture extending therethrough, of a screen

comprising a wire wound from end to end upon said frame, a second screen comprising a wire wound from side to side upon said frame, said screens extending across said aperture, said wires being adapted to be connected in parallel to a source of electricity, and cement filling in the spaces around those portions of the screens and screen-wires between the periphery of said aperture and the periphery of said screen.

2. The combination of a frame having an aperture therethrough, of a screen comprising a wire wound from end to end upon said frame and extending across said aperture, said wire being adapted to be connected to a source of electricity, and cement filling in the spaces around those portions of the screen between the periphery of said aperture and the periphery of said frame.

3. The combination of a frame thicker at its ends than it is intermediate of its ends and having an aperture extending therethrough, of a screen comprising a wire wound upon said frame, a second screen comprising a wire wound upon said frame, said wires being adapted to be connected to a source of electricity, said screens extending across said aperture, and cement filling around those portions of said screens between the periphery of said aperture and the periphery of said frame.

4. The combination with a liquid or gas conductor, of an electric heating element extending across the path of the liquid or gas through said conductor, said element including a frame having an aperture therethrough, a screen comprising a wire wound around said frame and extending across said aperture, and a filling of refractory material in the spaces and around those portions of said screen between the periphery of said aperture and the periphery of said frame.

In testimony whereof, I hereunto affix my signature, in presence of two witnesses.

IRVING E. ASKE.
